(57) **CLAIM**

The ornamental design for an ink cartridge, as shown and described.

DESCRIPTION

FIG. 1 is a front elevation view of my new design;

FIG. 2 is a top plan view thereof;

FIG. 3 is a right side view thereof;

FIG. 4 is a left side view thereof;

FIG. 5 is a rear elevation view thereof;

FIG. 6 is a top perspective view thereof; and,

FIG. 7 is another top plan view thereof without the environment covering the claimed design.

The broken lines are for illustration only and form no part of the claimed design.
